US00D926087S

(12) **United States Design Patent** (10) **Patent No.:** **US D926,087 S**
(45) **Date of Patent:** **** Jul. 27, 2021**

(54) **ELECTRIC WHEELCHAIR**

(71) Applicant: **WHILL, Inc.**, Kanagawa (JP)

(72) Inventors: **Hiroyuki Tsukamoto**, Yokohama (JP);
Masahiro Toriyama, Yokohama (JP);
Satoshi Sugie, Yokohama (JP)

(73) Assignee: **WHILL, Inc.**, Tokyo (JP)

(**) Term: **15 Years**

(21) Appl. No.: **35/508,884**

(22) Filed: **Sep. 26, 2019**

(80) **Hague Agreement Data**

Int. Filing Date: **Sep. 26, 2019**

Int. Reg. No.: **DM/205468**

Int. Reg. Date: **Sep. 26, 2019**

Int. Reg. Pub. Date: **Mar. 27, 2020**

(51) **LOC (13) Cl.** **12-12**

(52) **U.S. Cl.**

USPC **D12/131**

(58) **Field of Classification Search**

USPC D12/128-133; D21/686-691

CPC A61G 5/04; A61G 5/10

See application file for complete search history.

(57) **CLAIM**

The ornamental design for an electric wheelchair, as shown and described.

DESCRIPTION

The patent or application file contains at least one drawing executed in color. Copies of this patent or patent application publication with color drawing(s) will be provided by the Office upon request and payment of the necessary fee.

1. Electric wheelchair

1.1 : Front

1.2 : Back

1.3 : Right

1.4 : Left

1.5 : Top

1.6 : Bottom

1.7 : Perspective

The blue-colored parts in the reproductions are not part of the claimed design; the shading in the reproductions represents the three-dimensional shapes of the surfaces; and the shading does not illustrate surface ornamentation or decoration.

1 Claim, 7 Drawing Sheets
